JOSEPH WHITE, OF PISCATAWAY TOWNSHIP, NEW JERSEY, ASSIGNOR TO HALL PRINTING PRESS COMPANY, OF DUNELLEN, NEW JERSEY, A CORPORATION OF NEW JERSEY.

DELIVERY-TRAY AND SUPPORT.

1,211,511.

Specification of Letters Patent.

Patented Jan. 9, 1917.

Application filed October 19, 1912. Serial No. 726,592.

To all whom it may concern:

Be it known that I, JOSEPH WHITE, a citizen of the United States, residing at Piscataway township, State of New Jersey, 5 (post-office address Boundbrook, New Jersey), have invented certain new and useful Improvements in Delivery-Trays and Supports; and I do declare the following to be a full, true, and exact description of 10 said invention, such as will enable others skilled in the art to which it appertains to make use of the same.

In many forms of mechanisms, and particularly printing machines, it is often desirable to deliver sheets in small unit piles 15 for various reasons, such as to prevent the offsetting of wet ink and to hasten the drying thereof and the like. This is usually accomplished by placing relatively small 20 quantities of the sheets, as they come from the machine, on separate trays or holders. Sometimes these holders or trays are placed directly on the delivery board of the machine and removed when the machine is stopped 25 or between the delivery of successive sheets. Devices have also been made by which a plurality of trays are presented successively to the delivery mechanism so that a small quantity of sheets may be delivered to each 30 tray, which is then automatically removed.

My present invention provides a simple and efficient means by which a tray may be supported so that the sheets are delivered directly thereto until a quantity has accumulated, when the tray may be pushed out of place by the operator by the insertion of an empty tray between the successive operations of the delivery apparatus, the arrangement being such that the displacement of 40 the full tray by the empty one may occur so quickly that, even in machines in which the sheets are being delivered in rapid succession, it may take place between the delivery of the successive sheets. To this end, 45 I have provided a novel supporting means on which the trays may be rapidly moved into place and a stop to limit the motion of the tray along the support so as to locate it correctly. I have also provided a mechanism by which this stop is removed from 50 contact with the filled tray, by the act of inserting an empty one, and I have also constructed the support for the trays so that the insertion of an empty tray serves to push

a loaded tray off the support and out of the 55 way of the empty tray. From this lower position, the full tray is removed while the empty tray is being filled. The means which I have provided to accomplish these ends are extremely simple and yet efficient, 60 it being understood that simplicity is desired because of the large number of trays which usually compose a set for use in such a machine. If the trays were complicated, the necessary expense involved would be 65 greatly increased.

With these and other objects in view my invention consists of certain novel features of construction and arrangement of parts 70 as will be more fully described and pointed out in the appended claims.

In the drawing, Figure 1 represents a perspective view of my novel supports with a delivery tray thereon. In the figure, a portion of another tray which is being 75 moved into position is shown. No particular machine to which the supports may be attached is shown, it being understood that the device may be attached to any kind of a machine in which suitable supports for 80 the several portions of my novel device would be provided. Fig. 2 represents a section of one of the plungers shown in Fig. 1.

The corresponding parts are referred to both in the drawing and the following description by similar reference characters.

In the drawing, 10 represents the body of a tray or support for sheets which, in the particular form chosen for purpose of illustration, is composed of a thin flat board. 90 This member 10 may be made up of a series of slats or in any other manner, as may be desired.

11 and 12 are end members for the tray extending across the ends thereof and above 95 the top of the member 10, as shown. It will be understood that the tray may also be provided with corresponding side members if desired.

13 and 14 are a pair of parallel bars fastened in any suitable manner to the machine from which the sheets are to be delivered to the trays.

15 and 16 are pieces of any suitable material, preferably steel, attached to the tray 100 in any convenient place at one end thereof as, for instance, in the form illustrated, against the inner face of the member 11.

These members 15 and 16 are supporting members for the tray, extending beyond the edges thereof, and are preferably located at one end of the tray. The supports 13 and 14 are spaced apart so as to permit a tray to pass between them and be supported thereon by the members 15 and 16 engaging with the tops of the supports 13 and 14. The members 15 and 16 are suitably notched, as shown, to guide the tray as it moves along the supports 13 and 14.

17 and 18 are short auxiliary supports arranged to engage the bottom of the member 10, in the form illustrated, at the end 15 opposite the members 15 and 16. As will be seen by an inspection of the drawing, the tray when in place is supported at one end by the members 15-16, resting on the supports 13-14 and by the auxiliary supports 17-18 at the other end.

In order to properly locate the tray under the delivery mechanism, I provide a stop device. I prefer the form of stop device which I have illustrated, although of course 25 such a device is capable of wide variation. In the form illustrated, 19 and 20 are a pair of stops each attached to the side of pivoted members 21-22, these pivoted members being pivotally supported at 21^A-22^A, on any 30 suitable portion of the machine delivering sheets to the trays. These pivoted members are arranged so that the stops 19-20 rest either on top of the supports 13-14 or on top of the member 10 of the tray and are 35 arranged to engage with the inner face of the member 12 of the tray. It will be clear by inspection of the drawing that so long as these stops are in the position shown the tray cannot be moved to the left. The piv- 40 oted members 21-22 are so arranged that one portion of them extends parallel to the supports 13-14 with a curved portion, which is practically a cam surface, extending upwardly therefrom. In order to move 45 the tray into position, it is necessary to move the stops 19-20 out of the path of the mem- ber 11 and this is accomplished by the contact of the members 15-16 with the curved portions of the pivoted members 21-22 as 50 the tray is moved into place and when the members 15-16 are to the right of the pivoted members 21-22, as will be readily under- 55 stood by an inspection of the drawing. As will also be readily understood, when the members 15-16 pass from under the ends of the pivoted members 21-22, the latter drop, bringing the stops 19-20 into the path of the member 12 and the tray is brought to rest when the member 12 contacts 60 with the stops 19-20.

When the tray which is in position has been filled with sheets and the operator desires to insert an empty tray and to remove the full tray, he places the supports 15-16 65 of the empty tray on the ends of the bars

13-14 to the right of the stops 19-20 and moves such empty tray toward the left. The members 15-16 first move the stops 19-20 past the member 12 of the full tray and then the member 11 of the empty tray will contact with the member 12 of the full tray so that the full tray is pushed ahead of the empty tray. The empty tray continues its inward movement until the stops 19-20, which have now dropped into operative position, contact with the member 12 of the empty tray.

In many forms of machines, it will be possible to have the supports 13-14 and the auxiliary supports 17-18 long enough 80 so that the full tray would be supported as it is being pushed ahead of the empty tray until the empty tray is in position and then the full tray would be lifted from its supports. In many forms of machines, and particularly certain types of printing machines, this is not possible and to enable the removal of the full tray, I construct the tray supports in such a way that after the full tray is pushed ahead a short distance by the empty tray, the full tray will drop below the plane of the empty tray, so that the operator may withdraw it after the empty tray is in place and from the same point at which the empty tray was inserted. To this end, I 90 cut off the supports 13-14 so that they extend only a short distance beyond the position of the supporting members 15-16 when the tray is in operative position and I likewise shorten the auxiliary members 100 17-18. As will be seen by an inspection of the drawing, if the tray is moved a short distance to the left, the supporting members 15-16 will pass by the ends of the supports 13-14 and the bottom of the tray will pass 105 by the ends of the auxiliary supports 17-18. The tray will therefore drop bodily to a lower level. I provide a support to catch this tray as it falls, which support, in the preferred form, consists of parallel mem- 110 bers 23-24 attached in any suitable manner to the machine delivering the sheets to the tray, and to cushion the tray against the shock of falling, I provide a cushioning de- 115 vice which, in the form illustrated, consists of a number of spring-seated plungers 25 held in a pocketed member 26 attached to the members 23-24. In addition to the spring 27 supporting the plunger 25, I may arrange an air cushioning device comprising 120 a pocket 28 in the plunger 25 into which a rod or plunger 29 is adapted to engage. It will be understood that when the full tray is pushed off the upper supports by the insertion of an empty tray, it will move to the 125 lower plane represented by the tops of the members 23-24, the plungers 25 being pushed down until level with such supports. The operator then at his leisure removes the full tray by sliding it toward him or to the 130

right of the figure. The members 23-24 have an upwardly extended portion 30 to act as a stop for the full tray, the parts 15-16 contacting therewith to prevent the full tray being pushed beyond the ends of the supports 23-24.

While I have shown a simple, efficient and preferred form of my invention, it will be understood that there may be many modifications in the device illustrated, all of which fall within the scope of my invention. While I have shown a simple bar as a support and a supporting member attached to the tray and having notches to 15 guide the tray on such bar, it is obvious that I am by no means limited to this structure. This support may be arranged in such a way as to act directly on the tray itself instead of the member attached 20 thereto.

While I have shown my tray stop mechanism as composed of a plurality of stops, it is obvious that a single stop will answer for many purposes. It will also be obvious 25 that the stop may be engaged with the tray at any desired point or it may be made to engage either end of the tray with any suitable member attached thereto. It is also obvious that many variations of the 30 mechanism for supporting the stop may be used.

Having now described my invention what I claim as new is:

1. A pair of parallel supports spaced apart, and a delivery tray having supporting members on opposite edges of said tray at one end only thereof and projecting beyond said edges and constructed and arranged to engage said supports to support 40 said tray and to permit it to be slid along said supports.

2. A pair of parallel supports spaced apart, and a delivery tray having supporting members on opposite edges of said tray at one end only thereof and projecting beyond said edges and adapted and arranged to engage said supports to support said tray and to permit it to be slid along said supports, one of said supporting members being adapted to engage one of said supports to hold said tray in lateral position thereon as it is being slid along said supports.

3. A pair of parallel supports spaced apart, and a delivery tray having supporting members on opposite edges of said tray at one end only thereof and projecting beyond said edges and adapted and arranged to engage said supports to support said tray and to permit it to be slid along said supports, and a stop to limit the motion of said tray along said support.

4. A pair of parallel supports, spaced apart, and a delivery tray having supporting members on opposite edges of said tray at one end only thereof and projecting be-

yond said edges and adapted and arranged to engage said supports to support said tray and to permit it to be slid along said supports, and a removable stop to limit the motion of said tray along said support. 70

5. A delivery tray support constructed and arranged to permit trays to be moved horizontally thereon, a movable stop having a fixed position with relation to said support and constructed and arranged to 75 limit the motion of said trays on said support and automatic means to move said stop out of operative position as a new tray is moved into position on said support.

6. A delivery tray support constructed 80 and arranged to permit trays to be moved horizontally thereon, a movable stop constructed and arranged to limit the motion of said trays on said support, and a member on each tray, constructed and arranged 85 to move said stop out of operative position as a tray is moved into position on said support.

7. A pair of delivery tray supports, spaced apart, a plurality of delivery trays, each 85 provided with a supporting member on either side, arranged to engage said supports to support said tray and to permit it to be moved horizontally along said supports, a removable stop to locate each tray 90 in operative position on said supports, and means, operated by one of said supporting members, to remove said stop from operative position as the tray having said supporting member is moved into position on said support. 100

8. A delivery tray support constructed and arranged to permit trays to be moved horizontally thereon, a stop adapted to engage a tray as it is slid along said support 105 and to locate it in position thereon and a member to carry said stop, said member being constructed and arranged to be engaged and moved by a tray moving along said support so as to move said stop out of 110 operative position.

9. A delivery tray support, constructed and arranged to permit trays to be moved horizontally thereon, a removable stop constructed and arranged to engage a tray and 115 locate it in position on said support, said support and said stop being constructed and arranged so that, as an additional tray is moved along said support into position, it first engages and removes said stop from 120 operative relation with the positioned tray and then engages the positioned tray and moves it out of position as the additional tray is moved into position.

10. A delivery tray support constructed 125 and arranged to permit trays to be moved horizontally thereon, a plurality of trays each having a projection extending beyond the edge thereof, a removable stop arranged to limit the motion of the trays along said 130

support and a stop support constructed and arranged to be engaged by said projection as the tray is moved along said support, to remove said stop from the path of the tray and then to permit it to return to said path to locate said tray on said support.

11. A delivery tray support constructed and arranged to permit trays to be moved horizontally thereon, a delivery tray comprising a bottom section and a member at each end projecting above the bottom section, a removable stop constructed and arranged to engage one of said end members to locate said tray on said support and means on said tray to remove said stop from the path of the tray to permit one of said end members to pass and to permit said stop to return to operative position to engage the other end member as said tray is moved along said support.

12. A pair of delivery tray supports, spaced apart, and constructed and arranged to permit trays to be moved horizontally thereon, a tray adapted to be supported movably on said supports, said tray and said supports being constructed and arranged to permit both ends of said tray to drop simultaneously when said tray is moved beyond a predetermined point on said supports, and a removable stop to limit the motion of said

tray when moving along said supports, before it reaches said predetermined point.

13. A pair of delivery tray supports, spaced apart, and constructed and arranged to permit trays to be moved horizontally thereon, a tray adapted to be supported movably on said supports, said tray and said supports being constructed and arranged to permit both ends of said tray to drop simultaneously when said tray is moved beyond a predetermined point on said supports, and cushioning devices to receive said tray as it drops.

14. A pair of delivery tray upper supports, spaced apart, a delivery tray lower support located below said upper support, each of said upper and lower supports being constructed and arranged to permit trays to be moved horizontally thereon, a tray adapted to be supported movably on said supports, said upper supports and said tray being constructed and arranged to permit both ends of said tray to drop to said lower support simultaneously when said tray is moved beyond a predetermined point on said upper support.

JOSEPH WHITE.
